UNITED STATES PATENT OFFICE.

ARTHUR D. PRATT, OF SHORT HILLS, NEW JERSEY, ASSIGNOR TO THE BABCOCK & WILCOX COMPANY, OF BAYONNE, NEW JERSEY, A CORPORATION OF NEW JERSEY.

STEAM BOILER.

Application filed November 8, 1920. Serial No. 422,518.

To all whom it may concern:

Be it known that I, ARTHUR D. PRATT, a citizen of the United States, residing at Short Hills, in the county of Union and State of New Jersey, have invented certain new and useful Improvements in Steam Boilers, of which the following is a specification.

My invention relates to steam boilers and more particularly to those of the general Stirling type, and will be understood by reference to the accompanying drawings in which the figure is a vertical, longitudinal section of one embodiment thereof, the furnace of the boiler being shown broken away.

Referring to the figure, the boiler shown comprises transverse, upper steam and water drums 1, 2 and 3, and a mud drum 4, the upper drums being connected to the mud drum by means of banks of tubes 5, 6 and 7. I may use a single mud drum 4, as shown, or a series of connected mud drums, and I intend to cover both structures by the words "lower chamber" in the claims. The three upper steam and water drums must, however, be connected to this lower chamber, whether in the form of one drum or several connected drums. The steam space of the center drum 2 is interconnected with the front and rear drums by curved steam circulating tubes 8 and 9. The water spaces of the front and middle drums are connected by water circulating tubes 10, the upper row of which tubes support tilting 11. In the form illustrated, no water circulators are provided between the middle and rear steam and water drums.

A baffle 12 is supported on the tubes of the front bank and extends upwardly from the mud drum 4 to the upper end of the bank. The middle bank of tubes 6 is provided with a baffle 13 extending from the middle drum 2 downward toward the mud drum 4. Cross baffles 14 and 15 are provided at the rear of the rear bank 7. A superheater 16 of the usual construction is shown in the second pass of the boiler.

The gases from the furnace follow the direction indicated by the arrows, flow upward along the tubes of the bank 5 and downward through the second pass, and upward along the tubes of the bank 7 and out of the gas outlet 17.

In the form illustrated, the middle and rear steam and water drums are on substan-

tially the same level, which is higher than the level of the front steam and water drum. The main steam outlet 18 is connected to the rear steam and water drum in the form illustrated, and the feed water enters the rear drum through the pipe 19.

The drums are of the usual type, that is, made up of a shell sheet and a tube sheet, butt-jointed and secured with double longitudinal straps 20. In order to deflect the gases away from the drums 2 and 3, and to prevent direct impingement of the gases against the butt straps of the middle and rear drums, I provide a special baffle 21 which extends from the baffle 13 to the drum 3 below the butt straps 20, and as a means for supporting and protecting such baffle I utilize water tubes extending from the middle bank to the rear drum, so that such portion of these tubes on which the baffle 21 rests will be approximately horizontal. While these tubes may form a part of either the rear or middle bank of tubes, in the form illustrated, I have utilized the front row 22 of the tubes of the rear bank which, as shown in the drawings, have been separated from the remaining tubes of such bank until the lower portion thereof is substantially parallel with the tubes of the middle bank, but in the rear of the baffle 13. The upper portions of the tubes 22 are curved and extend rearwardly and connect into the rear drum 3.

With the tubes and baffles thus arranged, the gases passing upward in the rear pass cannot impinge against the butt straps 20, or any considerable portion of the rear steam and water drum which may be without water when the boiler is operated at high rating.

In the form illustrated, the special baffle 21 cooperates with the upper portions of the vertical baffle 13 to close the space between the upper rear and middle drums, to prevent impingement of the gases against the joints 20. If desired, the special baffle may extend entirely across the space between these two drums and contact directly with each of them, such special baffle being supported on the horizontal portions of the tubes 22.

I claim:

1. A steam boiler of the class described comprising three upper, transverse drums connected by banks of tubes to a lower

water chamber, a baffle extending downward from the middle upper drum at the rear of the bank connected to that drum, some of the tubes connected to the rear upper drum being directed at their upper portions toward said baffle, and a protecting baffle supported on said upper portions and extending from the rear upper drum to said baffle to protect the rear upper drum from 10 excessive heating.

2. A steam boiler of the class described comprising three upper, transverse drums connected by banks of tubes to a lower water chamber, the water spaces of the two 15 rearmost drums being unconnected except through the water chamber, baffling to direct the gases along said banks with a down-pass in the middle bank and an up-pass in the rear bank, the upper portions 20 of the front row of the rear bank of tubes being directed toward the middle bank of

tubes, and baffling to divert the gases from the space between the two rearmost drums, some of said last-named baffling being supported on said upper portions and the remainder extending along the rear of the 25 middle bank.

3. A steam boiler of the class described comprising three upper, transverse drums connected by banks of tubes to a lower 30 water chamber, baffling to direct the gases along said banks with a down-pass in the middle bank and an up-pass in the rear bank, a row of bent tubes connecting the lower water chamber with the rearmost 35 drum, and baffling to divert the gases from the space between the two rearmost drums, some of said last-named baffling being supported on the upper part of said row of bent tubes and the remainder extending 40 along the rear of the middle bank.

ARTHUR D. PRATT.
